ATTORNEY.

UNITED STATES PATENT OFFICE.

JOSEPH F. JOY, OF FRANKLIN, PENNSYLVANIA, ASSIGNOR TO JOY MACHINE COMPANY, OF PITTSBURGH, PENNSYLVANIA, A CORPORATION OF DELAWARE.

CONVEYER.

Application filed April 15, 1924, Serial No. 708,656. Renewed September 12, 1925.

To all whom it may concern:

Be it known that I, JOSEPH F. Joy, a citizen of the United States, residing at Franklin, in the county of Venango and State of Pennsylvania, have invented certain new and useful Improvements in Conveyers, of which the following is a specification.

This invention relates to certain new and useful improvements in conveyers of the well known chain and scraper type, and is particularly designed for use in loading machines of the type disclosed in my United States Letters Patent No. 1,306,064, dated June 10, 1919, although capable of general use.

An object of the invention is to improve the construction of the flights or scraper bars disclosed in my co-pending application for United States Letters Patent upon conveyers, filed Jan. 24, 1924, Ser. No. 688,183, whereby such scraper bars are made extremely strong and durable, although simple and inexpensive to manufacture.

Other objects will appear as the nature of the invention is better understood, and the same consists in the novel construction, combination and arrangement of parts herein-after more fully described, illustrated in the accompanying drawing, and claimed.

In the drawing, wherein like reference characters indicate corresponding parts throughout the several views,

Fig. 1 is a fragmentary view, partly in plan and partly in section, illustrating a portion of a conveyer constructed in accordance with the present invention,

Fig. 2 is a front elevation of one of the scraper bars, detached,

Fig. 3 is an enlarged end elevational view of the device shown in Fig. 2,

Fig. 4 is an enlarged transverse section taken on line 4—4 of Fig. 2, and

Fig. 5 is a view similar to Fig. 4 taken on line 5—5 of Fig. 1.

Referring more in detail to the several views, it will be understood that the present improvement relates to the construction of the endless conveyer member in the above mentioned patent and application comprising broadly the chains —35— connected by transverse scraper bars, as at —36—, the chains —35— broadly comprising pairs of inner links —37— and outer links —38—

pivotedly connected by pins —40— and spaced by rollers —41—.

In accordance with the present invention, the scraper bars —36— are of substantially inverted V-shape in cross section with the front leg or flange —F— vertical and the other flange —F'— longer and inclined, the latter flange being gradually increased in width from the ends to the center of the scraper bar so as to be of outwardly curved form as indicated at —C—. This gives great strength for withstanding the severe pressure of coal against the scraper bar when the conveyer is in use.

In order to further strengthen the scraper bar, and to enhance its loading or conveying efficiency, the flange —F'— is formed with a plurality of spaced ribs —R— which merge with the said flange adjacent its lower edge as at —M— and gradually increase in height as shown in Fig. 4 to the point where they terminate at the juncture of the flanges —F— and —F'—.

The chains are passed about sprocket wheels which preferably have guide rollers at their inner sides, and in order to permit passage of the scraper bars around these rollers, the ends of flange —F— are notched as at —N—.

The ends of the scraper bars are formed with pairs of opposite extending ears —36'— adapted for free slidable reception upon the inwardly extending studs or heads —42— provided on certain ones of the pivot pins —40—.

From the foregoing description, it will be seen that the present conveyer scraper bar embodies all of the advantages of that disclosed in my above mentioned co-pending application, and at the same time is more durable and efficient in operation.

Minor changes may be made without departing from the spirit and scope of the invention as claimed.

What I claim as new and desire to secure by Letters Patent is:—

1. In an endless chain and scraper conveyer member, a scraper bar of substantially inverted V-shape in cross section having one flange inclined and of gradually increased width from the ends to the center thereof.

2. In an endless chain and scraper conveyer member, a scraper bar of substantially

- inverted V-shape in cross section having one flange inclined and of gradually increased width from the ends to the center thereof, and a plurality of spaced transverse ribs formed on said flange. 3. In an endless chain and scraper conveyor member, a scraper bar of substantially inverted V-shape in cross section having one flange inclined and of gradually increased width from the ends to the center thereof, and a plurality of spaced transverse ribs formed on said flange, said ribs increasing in height toward and terminating at the point of juncture of the scraper bar flanges. 4. In an endless chain and scraper conveyor member, a scraper bar of substantially inverted V-shape in cross section having one flange inclined and of gradually increased width from the ends to the center thereof, pairs of opposed link pivot pins having inwardly extending studs, and ears formed upon the ends of said scraper bar freely telescoping onto said studs. 5. In an endless chain and scraper conveyor member, a scraper bar of substantially inverted V-shape in cross section having one flange inclined and of gradually increased width from the ends to the center thereof, pairs of opposed link pivot pins having inwardly extending studs, and ears formed upon the ends of said scraper bar freely telescoping onto said studs, the remaining flange of said scraper bar being vertical and having notches in the ends of its free edge.

In testimony whereof I affix my signature.
JOSEPH F. JOY.
